UNITED STATES PATENT OFFICE.

GILBERT A. BRADY, OF CHICAGO, ILLINOIS.

HEMMER FOR SEWING-MACHINES.

SPECIFICATION forming part of Letters Patent No. 268,779, dated December 12, 1882.

Application filed April 8, 1882. (No model.)

To all whom it may concern:

Be it known that I, GILBERT A. BRADY, a citizen of the United States of America, residing at Chicago, in the county of Cook and State of Illinois, have invented certain new and useful Improvements in Adjustable Hemmers for Sewing-Machines, of which the following, in connection with the accompanying drawings, is a specification.

10 In the drawings, Figure 1 is a perspective of a hemmer embodying my invention. Fig. 2 is a bottom view thereof. Fig. 3 is a side view thereof, and Figs. 4, 5, and 6 are plan views of the blanks from which the sheet-metal parts are made, respectively.

Like letters of reference indicate like parts.

In the drawings, A represents the presser-foot bar, and B the needle-bar, of a sewing-machine.

20 C is a presser-foot to which my attachment is applied.

D is the top plate. The blank from which this piece is made is shown in detail in Fig. 4. This blank consists of a piece of flexible sheet metal, of which a portion, a, constitutes the top plate proper. One corner of the part a is extended, as shown at a', and continuous with the part a is a wing, a''; also, on one edge of the part a'' is a lip or wing, a''', and the part a'' also has an extension, a'''. Between the parts a and a'' are the notches b and b'. c and c' are slots in the parts a and a'', respectively. d d are needle-holes. To prepare this blank for use in the attachment I bend it between the lines e e and lay the part a'' horizontally underneath the part a. I also roll the lip or extension a''' to form a scroll, E, and the opposite edge of the part a'', I bend along the lines e' e' to form a tongue or flange, F.

40 G is a sliding or adjustable plate, arranged between the upper and lower parts of the plate D—that is, between the parts a and a''. The blank from which the plate G is made is shown in Fig. 5, and consists of a plate of flexible sheet metal in the form of a parallelogram. In this blank I make a hole, f, to receive a screw-pin, which will be hereinafter referred to. To form this blank for use I bend it between the lines g g, which extend diagonally across the plate, as shown. This curve or bend is wide or open, so that a considerable space will exist between

the two horizontal parts of the plate, between which is the scroll a''' when the parts are all arranged together for use, as shown in Figs. 1 and 2.

H is a base-piece or supporting-tongue. This part is made of a flexible sheet-metal blank of the form represented in Fig. 6. One edge lies in a line at an angle to the lateral edges of the blank, as shown at h, and the opposite edge is curled up, as indicated in Figs. 1, 2, and 3.

H' is an arm or tongue extending horizontally from the curled-up edge of the plate H. The arm H' is permanently fastened to the under side of the plate G, after the latter is arranged between the parts a and a'' of the plate D, the said arm being laid for that purpose in the slot c', which is long enough to permit the adjustable plates to be moved back and forth between the parts a and a'', as will hereinafter more fully appear.

I is a screw-pin projecting vertically from the plate G and extending through the slot c.

J is a nut run upon the upper end of the pin I, and K is a washer arranged between the nut J and the plate D.

By bending the plate D in the manner described and shown a sufficient space is left between the parts a and a'' thereof to receive the plate G and allow it to be moved back and forth therein when the nut J is loosened; but by tightening this nut this movement will be prevented. As the plate H is permanently attached to the plate G, these two plates move together, and as the scroll a''' is fixed the curled-up part of the plate H may be set at a greater or less distance from the scroll a''', according to the width which may be desired for the hem. The turned-in end of the plate G is always in the same position with relation to the upcurled end or part of the plate H, and a slight space exists between this plate and the down and in turned part of the plate G. When the part a'' of the plate D is bent underneath the part a the extensions a' and a''' are brought together or directly opposite each other. The holes d d then register with each other, and that part of the slot c' which is not occupied by the arm H' registers with the slot c. I then fasten the extensions a' and a''' together without closing the space between the parts a and a'', and then fasten the extensions to the press-

er-foot C so that the needle-hole therein will register with the holes *d d*. The hemmer is then ready for use.

To apply the hemmer to the machine, I place 5 the presser-foot C on the presser-foot bar, and tighten the clamping-screw for securing it thereon. The goods are slipped in between the plate H and the indent portion of the plate G. As the edge of the goods strike the up- 10 turned part of the plate H they will be turned or folded over toward the scroll *a'''*, and will reach that scroll, and it will turn in the edge of the goods. The goods will thus be laid to form a hem, and the hem will be folded at both 15 edges—that is, there will be a fold to form the hem, and the edge of the part laid over to form the hem will be turned in underneath the part so laid over. As the machine is operated the goods will be fed along and stitched so as 20 to secure the hem. The hemmer, as will be perceived, may be adjusted to make either a very broad or a very narrow hem.

The hemmer, not regarding the presser-foot C and the adjusting-screw, is made in only 25 three parts or pieces, all of which may be made and arranged together with facility.

Any suitable means may be employed for connecting the plates G and H adjustably to the plate D.

30 Having thus described my invention, what I

claim as new, and desire to secure by Letters Patent, is—

1. An adjustable hemmer for sewing-ma- 35 chines, in which are combined the fixed plate D, consisting of the top part or portion, *a*, and under part, *a''*, having thereon the extensions *a'* and *a'''*, and in which are needle-holes, and the slots *c* and *c'*, respectively, the part *a''* having thereon the scroll E and lip F, the plate G, bent back underneath the scroll E and secured 40 adjustably between the parts *a* and *a''*, and the base-plate H, having a curled-up rear edge and a tongue, H', the latter being rigidly attached to the plate G, all operating together substan- 45 tially as and for the purposes specified.

2. An adjustable hemmer in which are com- 50 bined the fixed slotted plate D, consisting of the top part or portion, *a*, and the under part or portion, *a''*, having thereon the scroll E, all made in one blank or piece, the plate G, bent underneath the scroll E, the plate H, having an upturned edge and secured to the plate G, the presser-foot C, and a clamp or fastening for securing the plates G and H adjustably to the plate D, substantially as and for the purposes 55 specified.

GILBERT A. BRADY.
